UNITED STATES PATENT OFFICE.

PEIRCE CROSBY KELLY, OF PHILADELPHIA, PENNSYLVANIA, AND HERBERT ALTON LANDIS, OF HADDON HEIGHTS, NEW JERSEY, ASSIGNEES TO AMERICAN ENGINEERING COMPANY, OF PHILADELPHIA, PENNSYLVANIA, A CORPORATION OF PENNSYLVANIA.

FERRY BRIDGE.

Application filed November 22, 1922. Serial No. 602,577.

One object of our invention is to provide a relatively simple, substantial and practical combination of parts primarily for use in mooring ferry boats to a bridge or other structure, and the invention especially has to do with novel devices for insuring the deck of the bridge being flush with a deck of the boat when the two are moored together.

Another object of the invention is to provide an apparatus whereby a ferry bridge is so supported that when connected to a boat, it will be free to rise and fall with the latter in response to tide variations and variations in the live load.

We also desire to provide a novel device for releasably clamping together a boat and a ferry bridge so that these two shall be prevented from independent vertical movement, the invention especially contemplating a simple and conveniently operated controlling mechanism whereby the position of the bridge may be governed and the boat connected to or disconnected from said bridge with the utmost ease and in a minimum of time.

A further object of our invention is to provide a novel combination of ferry bridge, main and auxiliary weights and gripping mechanism actuated by certain of said weights whereby a boat may be immovably held to the bridge or released therefrom at will.

Our invention also contemplates novel combinations of apparatus for holding a ferry bridge to a boat by horizontally acting means, which apparatus shall require a minimum of attention and be of a relatively simple nature.

These objects and other advantageous ends we attain as hereinafter set forth, reference being had to the accompanying drawings, in which,

Fig. 1 is a front elevation of a ferry bridge constructed and equipped in accordance with our invention;

Fig. 2 is a plan of the gallows frame over the outer end of the bridge, together with the apparatus mounted thereon in accordance with our invention;

Fig. 3 is a plan, partly in horizontal section, illustrating the outer end of our ferry bridge;

Fig. 4 is an elevation partly in vertical section and on a larger scale than the pre-

ceding figures, illustrating the detail construction of the gripping mechanism with certain of the other parts of our device associated therewith;

Fig. 5 is an elevation of one of the auxiliary weights and its associated guides;

Fig. 6 is a diagram illustrating the electrical apparatus and connections for raising, lowering and holding the ferry bridge; and

Fig. 7 is a diagram of the connections and apparatus associated with one of the winch motors.

In the above drawings, 1-1 and 2-2 represent vertical frame members having their top portions connected by a pair of parallel horizontal members 3-3 constituting a gallows frame mounted upon a suitable structure or foundation adjacent the outer end of a ferry bridge 4, whose inner end is preferably, though not necessarily, hinged to a fixed structure, in the manner common in this art, so as to permit the outer end of said bridge to rise and fall or be moved vertically at will.

For movably supporting a certain proportion of the weight of the outer end of the ferry bridge, we provide main counterweights 5 hung from cables 6, which pass over sheaves 7-7 respectively and are also connected to opposite ends of a transverse member 8 extending under and connected to the bridge adjacent its outer or free end. These counterweights balance about 95% of the suspended dead load of the bridge, and for conveniently raising and lowering the outer end of the latter at will we provide an electric motor 9 operatively connected through suitable gearing to a drum 10 which with it is placed preferably at about the middle point of the top frame members 3.

From said drum cables 11-11 extend over sheaves 12-12 on the frame to auxiliary weights 13-13 vertically movable in guideways provided by frames 14 mounted at opposite sides of the outer end of the ferry bridge. Each of these auxiliary weights is so associated with its guideways that after being raised to a limited extent, it will engage the same and thereafter as it continues to rise, will lift the outer end of the bridge. For this purpose said weights are preferably provided with projecting lugs 15-15 operative in vertically extending slots 16 in the guideways or frames 14, and the weights are

each pivotally connected to one end of a lever 17 fulcrumed on the adjacent frame 14. The opposite end of each lever is connected through a link 18 with an arm 19 rigidly fixed to a shaft 20 mounted in bearings 21 under the bridge so as to extend transversely across one side of the outer end thereof and each shaft has also rigidly fixed to it a clamping or gripping lever 22. These levers 10 project outwardly beyond the ferry bridge so that when drawn upwardly by the links 18 they will engage the under part of a ferry or other boat and cooperate with suitably positioned shoulders such as are formed 15 by strong backs 23, likewise projecting beyond the forward end of the bridge, to grip or clamp said boat so as to removably hold it with its main deck flush with the deck or top surface of the bridge.

20 While the auxiliary weights with their frames and associated levers 17 are preferably placed at the extreme sides of the outer end of the bridge, the shafts 20 are so positioned that the clamping levers 22 will engage parts of a boat immediately adjacent to or in engagement with the outer end of the bridge between said auxiliary weights and under the strong backs 23. These latter are of any suitable construction and are 25 so placed that they will cooperate with the clamping levers 22 to grip the bow of a boat with a force depending upon the mass of the auxiliary weights.

For drawing the boat toward the outer 30 end of the bridge and preventing its moving horizontally away from the same, we mount upon said bridge a pair of mooring winches each consisting of a drum 24 connected through suitable worm gearing with an electric motor 25, preferably placing these winches at the extreme sides of the outer end of said bridge. The boats with which the bridge is to be used are equipped with devices such as eyes 26 in position to be engaged by mooring hooks 27 connected to the 35 ends of the cables from the drums 24 of the mooring winches and, as shown in Fig. 7, each of the motors 25 is connected in circuit with a suitable controller or switch 28 and also with an overload relay or contactor 29 which may be adjusted at will to automatically open the circuit of said motor when the 40 load thereon, and consequently the current flowing in said circuit, exceeds a predetermined amount.

The motor 9 for actuating the auxiliary counterweights is likewise connected in circuit with a hand operated controller 30 (Fig. 6) and with an automatic switch 31 having an arm 32 (Fig. 4) held resiliently by means not shown so as to be in a position where it may be actuated by one of said counterweights when this moves into a predetermined position. The position of the 45 arm 32 after it has been actuated by the

counterweight 13 is shown in Fig. 4. It is noted that the counterweight 13 is in its lowest position and resting upon the bridge. This automatic switch 31 is preferably of such construction that its movable contact 79 member normally engages a pair of contacts 33 and 34 as long as its arm 32 is disengaged from the lug of the auxiliary counterweight 13. When however said counterweight engages and actuates said arm, the movable 75 contact 35 of the automatic controller electrically connects two other contacts 36 and 37.

With the above described arrangement of parts, when a boat is to be moored to the 80 bridge after having moved into engagement with or immediately adjacent its outer end, the handle of the main controller 30 for the motor 9 is moved to its lowering position connecting a rotor 38 and a field winding 39 of said motor 9 in series-circuit relation and also energizing a solenoid brake, the energizing winding of which is indicated at 40 in Fig. 6.

The energization of the solenoid-brake 90 causes the release of the solenoid brake, permitting the shaft of the motor 9 as well as the drum 10 to move freely. The substantially simultaneous energization of the series-connected motor 9 results in the 95 swinging downwardly of the bridge 4 until the strong backs 23 rest upon the top surface of the main deck of the boat, which is then flush with the top surface of the bridge. Thereafter, the continued descent of the auxiliary weights 13 in the guide frames 14 causes said weights to swing the levers 17 on their fulcrums, thereby also swinging the clamping levers 22 up into engagement with the under part of the bow of the boat and causing this to be rigidly gripped between 100 said levers and the strong backs 23.

The mooring hooks 27 are now engaged with the eyes 26 and the controllers for the 105 motors 25 of the winches are operated to such position as to cause the drums 24 to wind in their cables. Said controllers after having been operated to this position, may be left therein, since when the boat X engages the outer end of the bridge, the further operation of the winches is automatically stopped by the opening of the overload 110 circuit breakers 29 in the circuits of their respective motors. The downward movement of the auxiliary weights above referred to, in bringing the movable contact 35 of the automatic controller into engagement with the stationary contacts 36 and 37, cuts off current from the motor 9 and forms a closed circuit, wherein the rotor 38 and the field winding 39 of said motor 9 are connected in series-circuit relation, whereby the motion of said rotor 38 may be rapidly damped.

115 The boat is now moored to the bridge and

the passage of heavy loads across the outer end of the latter onto or from said boat does not and cannot cause relative movement of the bridge and boat, although these structures are free to rise and fall together, since the present circuit arrangement is such that the energizing winding 40 of the solenoid 5 brake is still energized, causing the brake to be held off the shaft of the motor 9. All 10 necessity for gang planks is therefore avoided, loads passing over the end of the boat being sustained by the buoyancy of the latter as well as by the ferry bridge and relative movement being prevented by the 15 clamping levers 22 which may exert, for example, a gripping force of eight thousand pounds.

In casting off, the movable elements of the mooring winch controllers are first 20 thrown into such positions as to ease off the cables and are thereafter moved to a neutral position, whereupon the mooring hooks 27 may be disengaged from the eyes 26. The main hoist controller 30 is now operated to cause the motor 9 to raise the auxiliary 25 weights 13, thereby automatically releasing the clamping levers which swing downwardly to disengage the boat.

The continued operation of the motor 9 causes the lugs on the auxiliary weights to engage the upper ends of the slots of the guides 14 and then causes an upward movement of the outer end of the bridge until the strong backs are free from the boat deck, 30 whereupon the movable element of the controller 30 is brought to its neutral position. The motor is thus stopped and the solenoid 35 brake is automatically set, thereby holding the bridge immovably in its raised position above the boat deck level, ready to be lowered 40 so that its strong backs and clamping levers may be caused to grip the next boat coming in.

It is to be understood that the motors 25 45 are connected to the drums 24 of the mooring winches by self-locking worm gearing which, after said drums have been operated to wind up their cables and thus draw a boat into engagement with the bridge, will hold 50 said cables taut and prevent overhauling. The cables 11 for the auxiliary counterweights are kept taut by backweighting the drum 10, for which purpose an auxiliary cable 50 has one end connected to said drum 55 and passes over a sheave 51 to a small weight 52 hung on its second end.

From the above description it will be appreciated that we have provided relatively 60 simple apparatus for insuring the decks of the bridge and boat moored thereto being flush when the two are connected while permitting the automatic rise and fall of these connected structures under variations of load or tide. Owing to the simplicity of construction, there is no necessity for skilled

labor for operation or maintenance, and the invention effectually prevents accidents which have hitherto frequently occurred by reason of the relative movement of boat and bridge when heavy loads passed from one 70 to the other.

We claim:

1. The combination of a ferry-bridge structure to which a boat is to be moored; at least one strong back on said structure; and means adapted to exert an upward thrust on said boat tending to hold the same in engagement with said strong back. 75

2. The combination of a ferry bridge hinged at one end to a fixed structure; and means for releasably gripping the opposite end of said bridge to a boat to cause them to rise and fall together; with a weight for the bridge connected to control said gripping means, the gripping engagement involving an upward thrust on said boat. 80 85

3. In combination, a hinged ferry bridge; a weight; means for successively applying to and removing from said bridge the weight; with means actuated by said weight for releasably gripping the bridge to a boat when the weight has been applied to the bridge. 90

4. In combination, a ferry bridge; a weight; means for successively raising and lowering said weight from and to said bridge; at least one strong back for the bridge; and a member actuated by the weight adapted to exert an upward thrust against a boat when the weight is applied. 95 100

5. The combination of a hinged bridge having a shoulder; levers mounted on the outer end of said bridge; and mechanism including an actuating weight movable independently of said bridge for causing said levers to exert an upward thrust so as to hold the boat in engagement with said shoulder with its deck substantially flush with the top surface of the bridge. 105

6. The combination of a ferry-bridge structure to which a boat is to be moored; strong backs projecting from said structure; levers fulcrumed on the structure in positions to permit of a portion of a boat entering between them and the strong backs; with mechanism for actuating the levers to cause them to clamp said portion of the boat against the strong backs. 110 115

7. The combination of a bridge to which a boat is to be moored; strong backs projecting from said bridge; levers fulcrumed on the bridge in positions to permit of a portion of a boat entering between them and the strong backs; and bridge-lifting means including mechanism for actuating the levers to cause them to clamp said portion of the boat against the strong backs. 120 125

8. In combination, a bridge; a boat adjacent thereto; means for so moving the bridge that the deck thereof is contiguous with that of said boat; strong backs on the bridge 130

- adapted to extend over the deck of said boat; and motor-controlled, weight-actuated means for clamping the deck of said boat against said strong backs.
- 5 9. The combination of a ferry-bridge structure to which a boat is to be moored; clamping means for securing a boat to said structure to prevent its relative vertical movement; and independent means for holding said boat to prevent its horizontal movement relatively to said structure, said means comprising an electrically operated winch and automatic control means therefor.
- 10 10. The combination with a ferry-bridge structure to which a boat is to be moored; of means for so securing a boat to said structure as to prevent relative vertical movement, said means including a lever positioned to exert an upward thrust on the end 20 of the boat.
- 11 11. The combination of a bridge; clamping means for securing a boat to the bridge to prevent its vertical relative movement; electrical control means for said clamping means; and independent means for exerting a horizontal force on the boat to hold it toward said bridge and prevent its disengagement from the clamping means.
- 12 12. The combination of a ferry-bridge structure to which a boat is to be moored; an electrically driven mooring winch including a cable for holding a boat to said structure; and means for automatically cutting off current from the motor of said winch 35 when the boat has been brought into engagement with the structure.
- 13 13. The combination of a bridge; a mooring winch thereon including an electric motor and a cable for mooring a boat to the bridge; with an overload circuit breaker in circuit with said motor set to cut off current therefrom when the load on said motor is increased beyond a predetermined amount by engagement of the boat with the bridge.
- 45 14. In combination, a bridge having raised and lowered positions, a motor; means for operatively associating said motor and said bridge; said means including a movable weight carried by said bridge when it is in its lowered position only; and a control switch for said motor, said switch being operated by said weight.
- 50 15. In combination, a bridge having raised and lowered positions; a weight resting on said bridge when it is in its lowered position only; a motor for raising the weight from said bridge and subsequently raising both the bridge and the weight; controlling means for determining the operation of said motor; and brake mechanism for holding said weight and bridge in the raised position; said controlling means being further adapted to effect the operation of said brake mechanism.
- 55 16. In combination, a bridge; gripping means adapted to secure said bridge to a boat; a weight for actuating said gripping means; a motor for raising the weight to release the boat; said motor also raising said bridge; brake mechanism for the motor whereby said weight and bridge may be held in a raised position; and controlling means for said motor and said brake, said controlling means effecting the inoperation of said brake when said weight is operating on 75 said gripping means.
17. In combination, a bridge having raised and lowered positions; gripping means for securing said bridge to a boat; a weight for actuating said gripping means; independent means for holding a boat to the bridge by a horizontally acting force; a motor for raising said weight to release said gripping means, said motor also being adapted to raise said bridge; a brake adapted to hold said weight and bridge in a raised position; and controlling means for said motor and said brake, whereby the brake may be rendered effective when the bridge has moved to its raised position and the motor substantially simultaneously rendered ineffective.
18. In combination, a hinged bridge; main weights counterbalancing the greater portion of the weight of said bridge; auxiliary weights; a motor for raising and lowering said auxiliary weights; gripping means operated by said movable auxiliary weights; and means whereby said motor becomes operative to raise said bridge and said weights at will.
19. In combination, a hinged bridge; main weights counterbalancing the greater portion of the weight of said bridge; auxiliary weights; a motor for raising and lowering said auxiliary weights; means whereby said motor becomes operative to raise said bridge and said weights at will; with mechanism controlled by the auxiliary weights for clamping a boat to the bridge when the latter is lowered.
20. The combination of a bridge hinged at one end to a fixed structure; main weights connected to the opposite end of the bridge and counterbalancing the greater part of the weight of said end; frames on said end of the bridge; auxiliary weights movably guided in said frames and adapted to operatively engage the same; a motor operative upon said auxiliary weights and connected to raise or lower them with the outer end of the bridge at will; clamping levers actuated by the movement of said auxiliary weights in said guide frames; and strong backs on the bridge positioned to cooperate with the clamping levers to hold the deck of a boat flush with the deck of the bridge when the auxiliary weights are lowered thereon.
21. In combination, a ferry bridge; weight-actuated mechanism for exerting an upward thrust on the under side of a boat; and elec- 130

trical control means for said mechanism adapted to permit said boat and said bridge to rise and fall together.

22. A movable bridge; a motor; means for operatively associating said bridge and said motor; said means including a weight; and a switch operated by said weight.

23. A movable bridge; a motor; means for operatively associating said bridge and said 10 motor; brake mechanism for said motor; and controlling means for said brake and said motor, said controlling means being operative to render effective said brake and to

render ineffective said motor and thereafter to render ineffective said motor only. ¹⁵

24. In combination, a movable bridge; a movable weight; a guiding frame for limiting the path of travel of said weight independent of said bridge; a motor operatively associated with said weight; a brake for said 20 motor; a control switch for said motor; and means for controlling said brake and said motor.

PEIRCE CROSBY KELLY.
HERBERT ALTON LANDIS.
